(57) **CLAIM**

The ornamental design for a fly trap, as shown and described.

DESCRIPTION

FIG. 1 is a perspective view of a first embodiment of a fly trap showing my new design;

FIG. 2 is another perspective view thereof;

FIG. 3 is a front elevational view thereof;

FIG. 4 is a rear elevational view thereof;
FIG. 5 is a right side elevational view thereof;
FIG. 6 is a left side elevational view thereof;
FIG. 7 is a bottom plan view thereof; and
FIG. 8 is a top plan view thereof;
FIG. 9 is an exploded front elevational view of the first embodiment of the fly trap;
FIG. 10 is an exploded rear elevational view thereof;
FIG. 11 is an exploded perspective view thereof;
FIG. 12 is a front elevational view of a trap element of the first embodiment of the fly trap, shown separately for ease of illustration;
FIG. 13 is a rear elevational view thereof;
FIG. 14 is a left elevational side view thereof;
FIG. 15 is a right elevational side view thereof;
FIG. 16 is a bottom plane view thereof;
FIG. 17 is a top plane view thereof;
FIG. 18 is a perspective view thereof;
FIG. 19 is a perspective view of a second embodiment of the fly trap showing my new design;
FIG. 20 is another perspective view thereof;
FIG. 21 is a front elevational view thereof;
FIG. 22 is a rear elevational view thereof;
FIG. 23 is a right side elevational view thereof;
FIG. 24 is a left side elevational view thereof;
FIG. 25 is a bottom plan view thereof; and
FIG. 26 is a top plan view thereof;
FIG. 27 is an exploded front elevational view of the second embodiment of the fly trap;
FIG. 28 is an exploded rear elevational view thereof;
FIG. 29 is a perspective exploded view thereof;
FIG. 30 is a front elevational view of a trap element of the second embodiment of the fly trap, shown separately for ease of illustration;
FIG. 31 is a rear elevational view thereof;
FIG. 32 is a left side elevational view thereof;
FIG. 33 is a right side elevational view thereof;
FIG. 34 is a bottom plane view thereof;
FIG. 35 is a top plane view thereof; and,
FIG. 36 is a perspective view thereof.
The broken lines in the drawings depict portions of the fly trap that form no part of the claimed design.
